WILLIAM C. BAXTER, OF BEVERLY, MASSACHUSETTS, ASSIGNOR TO UNITED SHOE MACHINERY CORPORATION, OF PATERSON, NEW JERSEY, A CORPORATION OF NEW JERSEY.

MACHINE FOR USE IN THE MANUFACTURE OF SHOES.

Application filed July 25, 1921. Serial No. 487,394

This invention relates to the manufacture of shoes, and is herein exemplified in its application to the molding of the toe portion of upper materials to give them substantially 5 the shape which they are to have in the finished shoe. It will be recognized, however, that in many of its important aspects the invention is not limited to the shaping of the toe portion of upper materials, nor to the 10 shaping of uppers as distinct from other shoe parts, and that in still other aspects the invention is not limited to molding in the treatment of uppers or other shoe materials.

Among its objects the invention has in view 15 important economies in shoe manufacture and uniform excellence in the quality of the product. Even in the present comparatively advanced stage of development of the shoemaking art, many operations depend for success 20 upon the exercise of great skill and judgment by the workmen, thus entailing a high labor cost, and this is conspicuously true of the shaping of the upper materials. In shaping the toes of uppers, for example, much care 25 and skill are needed, not only to conform the upper closely to the characteristically irregular curvature of the last or other shoe form, but also to gather and shape the marginal portion of the material smoothly and 30 uniformly as required for the appearance of the shoe and for successful results in subsequent manufacturing operations, and to establish correctly and in accordance with a predetermined standard the lines of the upper 35 characteristic of the given style of shoe. Even with the exercise of the greatest care and skill obtainable at a high labor cost, the difficult and critical operations involved in upper shaping often fall short of that degree 40 of accuracy and uniformity which is recognized as essential for the best shoemaking.

In view of the above mentioned and other conditions and with the general object above set forth, the present invention, in its illustrative embodiment, provides a novel machine organization designed for standardization in the shaping of upper materials. A 45 very important feature of the organization, which contributes directly to uniformity of 50 the product and to the elimination of the need for a high degree of skill on the part of the workman, consists in the combination of

means for operating upon the material and means for jigging the material to position it relatively to the means which operates 55 upon it. That is, as herein exemplified, there is provided means for insuring by engagement with positioning surfaces formed on the upper in predetermined relation to a characteristic thereof the proper position of the 60 upper in relation to the upper-shaping means in respect to such movement as might affect the accuracy of the shape imparted to the upper by said means. The machine herein shown comprises means for utilizing jig holes 65 formed in the marginal portion of the toe of the upper to position the upper in predetermined relation to the upper shaping means. The means illustrated for use in jigging the material, in which also an important feature 70 of novelty is to be recognized, comprises a presenter adapted to engage the work and move it into predetermined relation to the operating means and then to withdraw from the work. Still other important features are 75 to be recognized in an organization of means for jigging the material and means for operating upon the material in a manner not only to effect the required shaping operation but also to insure effective control of the material to maintain it in its jigged relation to the operating means. In the machine illustrated the desired results are secured by 80 clamping the margin of the upper in the position determined by the jigging, and further 85 in the course of the upper shaping operation by clamping the intermediate portion of the toe of the upper against the form, and subsequently clamping the upper also about the end of the form while its margin is shaped 90 over the form, thus maintaining an effective control of the jigged upper by clamping pressure in one or more locations throughout the upper shaping operation.

In another aspect the invention presents 95 various features of novelty in an organization of means for shaping the upper materials, comprising a novel construction and arrangement of means for shaping the material about a form and for molding its margin inwardly over the form, the machine 100 illustrated having means for molding the margin of the upper to produce inturned and upstanding portions adapted to conform sub-

stantially to the feather and the rib of a welt shoe insole. Among its other features, the invention provides novel means for clamping and controlling the margin of the upper and 6 novel means for wiping the upper heightwise of the form and for clamping it about the form. As applied to an organization wherein the upper is permitted to set until it has acquired permanently the shape imparted to 10 it, the invention further provides for relaxing the clamping pressure about the lateral periphery of the form to avoid marking the upper by the heavy forming pressure. While the invention, in many of its aspects, is not 15 dependent for utility nor limited to the shaping of uppers off the last, the machine illustrated is designed for molding the toes of uppers to give them substantially the shape which they are to have in the finished shoes 20 before the uppers are mounted on their lasts. Aside from the economies obviously involved in the elimination of the skill and care heretofore required in toe lasting, and the other advantages hereinbefore discussed, this 25 effects also a saving in lasts and other equipment due to reduction of the time the shoes must remain upon their lasts, and by reason of the heavy molding pressure to which the uppers may be subjected off the last contributes as well to permanence of shape in 30 the finished shoes.

Still another feature of the invention is to be recognized in a novel organization of means for shaping the work and means for trimming it, the machine illustrated having a trimmer which is movable in a predetermined path to trim the upstanding margin of the upper round the toe while the upper is under molding pressure. In an organization such 35 as illustrated, in which the upper is jigged to position it in predetermined relation to the upper shaping means, the provision of trimming means relatively to which the upper is also jigged insures a high degree of accuracy in the trimming operation. In connection with molding the end of the upper off the last, a further important advantage in trimming the margin, as required for example prior to the inseam sewing operation, 40 while the upper is under molding pressure, arises from the fact that the upper is then under better control for the trimming operation than at any subsequent stage in the manufacture of the shoe prior to the sewing 45 of the inseam.

The features of the invention hereinabove discussed, as well as other features involved in various details of construction and combinations of parts not specifically referred 50 to in the above general discussion, will now be more particularly set forth in connection with the accompanying drawings and pointed out in the claims. While the invention is herein illustrated in its application to welt 55 shoe work, it will be recognized that in many

of its aspects the invention is not limited to welt shoe manufacture.

In the drawings:

Figure 1 is a general view of the machine in side elevation, with some of the parts broken away and others shown in section, the parts being shown in the position which they assume at the end of the first stage of the cycle with an upper held under molding pressure; 75

Fig. 2 is a horizontal section on the line 2—2 of Fig. 1, with parts of the mechanism sectioned on a lower plane;

Figs. 24 and 25 are top plan views, showing the trimmer and its path of movement in trimming surplus upper from the upstanding flanges formed at the ends of different 20 uppers; and

Fig. 26 is a perspective view of the toe end portion of an upper after it has been molded and trimmed and the waste material detached, the waste material being indicated by broken 25 lines.

When the end portion of an upper has been shaped about the form as hereinafter described, it should preferably be permitted to set, to insure that when removed from the 30 form it will permanently retain its molded shape. To assist in holding the end of the upper in shape a stiffener may be placed between the leather or cloth forming the shoe upper proper and the lining. There are 35 various kinds of shoe end stiffeners which may be advantageously employed, but in the present exemplification of the invention a shoe end stiffener that may be rendered pliable by heat or moisture is employed and the 40 illustrated machine is more especially adapted for the treatment of the ends of shoe uppers having stiffeners which are rendered pliable by heat.

The machine shown is of the twin type, one 45 of the two mechanisms being adapted to treat the uppers of right shoes and the other those of left shoes, this arrangement also permitting one upper to set to the molded shape while the other is being placed in the machine 50 and subjected to molding pressure. Except as modified for the treatment of right and left shoes, the two mechanisms are similar in construction and mode of operation, so that a description of one will suffice for both.

The machine frame is of suitable character to support the operating parts, and as shown comprises the side frame members 1 upon which is mounted a top or table portion 2. Extending between the side members 1 is 60 the main driving shaft 3 which may be appropriately driven continuously from any suitable source of power. Preferably the driving shaft 3 is driven by an electric motor 4, operatively associated with a transmission shaft 5 connected to the driving shaft 3

through a suitable train of gearing which is typified at 6 (Fig. 3). The train of gearing may be of any appropriate character, the essential in this respect being that rotative movement of the transmission shaft 5 may be 70 transmitted to rotate the driving shaft 3.

Extending transversely of the driving shaft 3 and mounted in suitable bearings 7 and 8 carried by the machine frame is the clutch shaft 9 driven through a train of 75 mechanism from the driving shaft 3. In the present instance the driving shaft 3 has secured thereto a spiral gear 10 which meshes with a spiral gear 11 formed on or secured to a clutch member 12 loosely mounted on the 80 clutch shaft 9. A clutch member 13 is splined to the clutch shaft 9 and is under the control of the workman who may, at will, engage the clutch members 12 and 13, or disengage them, and thereby either start or stop the rotation of the clutch shaft. To this end the clutch member 13 is provided with a grooved portion 14 which is embraced by the end portion of an arm 15, Fig. 2, mounted for sliding movement on a guide or rod 16. Connected to the hub portion of the arm 15 is a rod 17 which is connected to a hand lever 18 mounted on a supporting rod 19 held in the machine frame. In the construction shown the hand lever 18 has a downwardly-extending portion 20 which is connected by a link 21 to the shifting rod 17, the construction being such that by manipulation of the hand lever 18 the workman may throw the clutch members 12 and 13 into or out of engagement. The hand lever 18 may be held in the position to which it is moved by means of a bracket or arm 22 having notched portions such as 23, in which the hand lever may catch at its extreme positions. The controlling 100 means thus provided is adapted for use to stop the machine at any point in its cycle independently of the normal starting and stopping means hereinafter described.

Secured to the clutch shaft 9 is the worm 24, Figs. 1 and 2, which is engaged with a worm wheel 25 mounted on a hub 26, Fig. 2. Between the side frame members extends a cam-carrying rod or shaft 27 on which the hub 26 of the worm wheel 25 is rotatably 110 mounted. At each side of the hub 26 the rod or shaft 27 carries a sleeve 28 on which cams are mounted for effecting movements of the operating parts of the corresponding 115 half of the machine in the formation of the ends of shoe uppers into their final shape.

The sleeves 28 are independent, and either one may be selectively connected to the hub of the worm wheel 25 for rotative movement therewith by clutch mechanism of any preferred type. In the construction shown each of the sleeves 28 is provided with a clutch pin 29 having a clutching portion 30 adapted to be engaged with and disengaged from a hardened metal ring 31, mounted fast in a 120

side portion of the hub 26, as more clearly indicated in Fig. 2. Each of the clutch pins 29 is provided with an outwardly-extending pin 32 which engages a ring 33 mounted on the corresponding sleeve 28. Each of the rings 33 is normally under the influence of a spring 34 tending to rotate the clutch pin 29 in a direction to engage the clutch pin with the ring 31 in the hub 26 of the worm wheel 25 to effect rotative movement of the sleeve. Each of the rings 33 is provided with two shoulders 35 (Fig. 1) which are adapted to contact with a clutch disengaging member 36 under control of the workman. Since there are twin mechanisms, each of which is to be selectively operated, the clutch engaging and disengaging mechanisms may be similar, and a description of one will suffice for both. In the present instance the member 36 is mounted for rocking movement upon the support 19, Fig. 1, and has a downwardly-extending portion 37 which is normally under the influence of a spring 38 tending to hold the member 36 in position for engagement with one of the shoulders 35. It is desirable that after the workman has tripped the clutch disengaging member 36, such member shall move back into position for engagement with the succeeding shoulder 35, without further attention on the part of the workman, and bring the connected sleeve 28 to rest. To this end the downwardly-extending portion 37 has pivotally mounted thereon at 39 a trip block 40 normally held in the position indicated in Fig. 1 by a spring 41. A treadle 42 is pivotally mounted at 43, and has an end portion 44 adapted to engage and ride over the end of the block 40 when the treadle is depressed; and a spring 45 returns the treadle to its normal position, as indicated in Fig. 1, when the foot of the workman is removed. Should the workman, however, by oversight, fail to remove his foot from the treadle, the trip block 40 will tilt after the end 44 of the treadle has passed its operating end, and permit the clutch-disengaging member 36 to return to clutch-disengaging position.

Pivotedly mounted at each side of the machine for swinging movement about a centre 46 on the top of the machine frame, Fig. 1, is a form carrier 47 having connected thereto at 48 an operating member 49 which extends downwardly and is under control of a cam mechanism on the corresponding sleeve 28. In the construction shown the operating member 49 has a head 50 through which passes the upper end of a rod 51 connected at 52 to an arm 53 mounted on a rod 54 supported at the rear of the machine frame. Extending from the arm 53 is a stud or roll 55, Figs. 1 and 5, which lies within a cam groove 56 formed on a cam 57 carried by the sleeve 28.

When the upper has been laid about the

form by the downward movement thereof, and prior to the inwiping movement of the wipers, as will hereinafter more fully appear, it is desirable that the form continue its downward movement far enough to permit the wipers to wipe the upper over the marginal edge portion of the form without injuring the upper, and thereafter to cause the form to press the inturned edge portion of the upper yieldingly against the lower surface of the wipers, and the cam 56 is appropriately shaped to effect these results. To effect the upward yielding pressure of the form against the inturned upper, a spring 58 is interposed between a collar 59 on the rod 51, Fig. 1, and the head 50, the upper end of the rod 51 having connected thereto the collars 60, and the construction being such that after the form has been lowered to permit the inwiping movement of the wipers, the rod 51 will be raised by the cam to compress the spring 58 and yieldingly uplift the form against the overwiped portion of the upper.

Mounted upon the head portion 2 of the machine, beneath the cover plates 61, are wiper holders 62 which carry wipers 63. Guiding slots 64 formed in the wiper holders are engaged by pins 65 passing through the cover plate to direct the movement of the wipers. Each of the holders 62 is connected by a link 66, Fig. 3, to a crosshead 67 having a rearwardly-extending portion 68 (Fig. 1) connected to toggle members 69 and 70 jointed together at 71. The toggle member 70, Fig. 1, is pivotally connected to a yielding abutment which may be conveniently formed by a rod 72 having collars 73 between which and the machine frame 2 is interposed a spring 74, the construction being such that when the toggle is straightened as indicated in Fig. 1, the wiper holders and the wipers will be moved to overwiping position with provision for yield. Adjustable stops preferably in the form of threaded nuts 75 limit the movement of the rod 72 under the impulse of the spring 74.

Connected to the toggle at the joint 71 is the toggle-operating means which, in the construction shown, comprises a head 76 and an adjustable toggle operating rod 77, Fig. 1. The lower end of the operating rod 77 is connected at 78 to an arm 79 pivotally supported by the rod 19. To impart operative movement to the rod 77 and the wipers, the arm 79 carries a stud or roll 80, best shown in Fig. 4, which lies in a cam groove 81 formed in the side of a cam wheel 82, Figs. 2 and 4. It may be desirable in some cases to limit the breaking movement of the toggle, which may be appropriately effected by means of a stop 83, Fig. 1, adjustably mounted in the head 76 and adapted to engage a projection 84 secured to the top portion 2 of the frame.

For purposes of the present invention there

is provided means for jiggling the upper to position it in predetermined relation to the form by engagement with the upper in jig holes formed in its margin at opposite sides of the toe in predetermined relation to a characteristic of the upper. The predetermined position of the end of the upper relatively to the form when the upper is placed in the machine is secured, in the construction shown, by the aid of a presenter which is constructed and arranged to support the upper in inverted position. The wipers 63 are each provided with co-operating positioning means which, in the present instance, are in form of slots 85 the walls of which are adapted to be engaged by portions of the presenter to position the upper. The presenter may be variously constructed, but as shown it comprises the two side arms 86 which are arranged a sufficient distance apart to permit the entrance of a portion of the upper. At the forward end of each arm the presenter has a projection or upper engaging portion which, in the present instance, comprises a pin 87, Fig. 12, the ends of the pins being reduced in diameter for engagement in the jig holes in the upper. The two portions 86 of the presenter may be extended to form a handle portion 88, Fig. 23, at the rear of the upper as a convenient means for manipulating the presenter to place the upper in the machine. The presenter may be constructed of resilient metal to adapt it for uppers of different shapes and sizes.

The upper which is to be placed in the machine is provided with positioning surfaces which are preferably formed by jig holes 89 made in the upper at separated points located at predetermined distances from a datum point, as for instance, the back centre line of the upper as at 90, Fig. 23, the construction being such that if all shoe uppers of the same size and style are provided with similarly located jig holes and the uppers are presented to the form by reference to such jig holes, the length, lateral position, and angularity of the molded ends of all the uppers of the series will be identical. Where the end of the upper is provided with a tip 91 which is secured to the vamp 92 by fastenings, as indicated in Fig. 22, the jig holes 89 may be formed on the vamp at predetermined distances from the back centre, and on the tip at predetermined distances from the front centre, such that when the tip and the vamp are assembled together, and the jig holes of the vamp and the tip are brought into matching relation, the length, lateral position, and angularity of the tip with reference to the vamp will be determined. As indicated in Fig. 22, the jig holes 89 may advantageously be formed between the lines of stitches which secure the tip to the vamp.

In presenting a shoe upper to the machine for treatment, the jig holes 89 in the end of

the upper are engaged by the projecting pins 87 of the presenter, and the main portion of the upper at 93 will extend between and be supported by the side members of the presenter, substantially in the position indicated in Fig. 23. With the upper in predetermined relation to the presenter, the workman has simply to move the presenter to bring the pins 87 thereof into the positioning slots 85 of the wipers until the pins engage the locking end portions 94 of the slots, which thereupon automatically determine the relation of the presenter and wipers, and consequently the position of the outspread upper with relation to the form. In order to assist in guiding the presenter and its supported upper into proper relation to the wipers, there are provided on the pins 87, in the construction herein shown, ledges 95 which are spaced below the upper supporting shoulders on the pins a distance substantially equal to the thickness of the wipers and are arranged to engage the lower surface of the wipers as the pins are moved inwardly along the slots 85. The relation of the presenter and the upper to the wipers when the upper is in position for the molding operation is indicated in Fig. 11.

When the end of the shoe upper has been placed in predetermined position with relation to the form, as above described, it is desirable that the upper be freed from the presenter and clamped in position for treatment by the machine. In the construction shown the outspread upper is held upon the top surface of the wipers by clamps, which as they are moved to operative or clamping position, assist in disengaging the presenter from the upper. The action of the clamps is preferably made yielding, so that the marginal portion of the upper may be partially withdrawn from between the clamps and the wipers as the upper is laid about the form.

The clamps for holding the marginal portion of the upper upon the wipers may be in the form of plates 96, Figs. 3, 11, 13 and 15, arranged to co-operate respectively with the different wipers. While in some cases it is not necessary, yet it is preferable to form the clamping plates 96 so that when they are in clamping position they will exert a substantially continuous clamping action round the end portion of the upper which is to be molded; and since the two clamping members on each of the twin machines are identical, a description of one will be sufficient.

Secured to and movable with the wiper holder 62 is the stud 97, Figs. 3 and 11, which passes through an elongated slot 98, Fig. 3, formed in the cover plate 61. If desired, a slide 99 may be carried by the stud 97 to cover the elongated slot 98 more or less as the wiper plate and the stud are moved relatively to the cover plate. Connected to the stud 97 is the clamp carrying arm 100 which

has an elongated slot 101 engaging a cross pin carried by the stud. Pivotally mounted on the end of the arm 100 at 102, so as to maintain at all times a substantially parallel relation to the plane of the wipers, is the clamping plate 96. A link 103 extends between the arm 100 and a stud 104 mounted on the wiper holder, and is normally in an inclined position when the clamp carrying arm 100 is raised, as indicated in Fig. 11. When, however, the clamp carrying arm 100 is depressed, as will be presently described, the link 103 serves to move the clamp 96 inwardly and bring it into closer relation to the edge portion of the wiper, with which it co-operates. An advantage in thus engaging the margin of the upper by the clamps close to the edges of the wipers is that uppers may be cut as small as is consistent with other operations of the molding mechanism without interfering with the proper function of the clamps. By reference to Fig. 13 it will be noted that when the clamps are in clamping position the links 103 are still inclined to the horizontal, and consequently the subsequent withdrawing movement of the clamps is outward from the edge of the form as well as upward. This insures that the clamps will not interfere with the margin of the upper which may in the final retracting movement of the clamps project upwardly inside of the inner edges of the clamp members.

The clamp-carrying arm 100 is preferably constructed with two side members, as indicated in Fig. 3, and through the space separating the side members extends a stud 105 which is secured to the wiper holder 62. Between the two side members 100 constituting the clamp-carrying arm, is the sleeve 106, Fig. 21, having the upper and lower flanges 107 and 108, the construction being such that should the sleeve 106 be raised or lowered, it will operate upon the clamp carrying arm to similarly move the clamp. The sleeve 106 has an upwardly extending portion 109 provided with slots 110 into which project the ends of pins 111, Fig. 20. The pins 111 are carried by a sliding member 112 to the upper end portion of which is adjustably connected a cap piece 113. Mounted in a socketed portion of the stud 105 is a spring 114, the normal tendency of which is to lift the sleeve 106 and to correspondingly lift the associated clamp carrying arm 100. Between the lower end of the cap piece 113 and the top of the sleeve portion 109 is a spring 115 which, when compressed by the downward movement of the cap piece 113, yieldingly forces the sleeve 106 downwardly to carry the clamp into clamp-
ing position.

The present invention provides means for automatically operating the clamps to the end that when the presenter has moved the end of the shoe upper into predetermined position relatively to the form, the clamps may

be operated to clamp the marginal portion of the outspread upper and to move the presenter in a direction to disengage it from the upper. Clamp-operating arms 116 are pivotally mounted on the top of the machine frame at 117, Figs. 1 and 3. In the present instance, the operating arms 116 are carried by a sleeve 118 which is mounted for rocking movement about the axis 117 and has a rearwardly-extending arm 119, Figs. 1 and 3, to which is connected one end of an operating rod 120, the lower end of which is connected at 121 to an arm 122 mounted for rocking movement on the support 54, Figs. 1 and 4. The arm 122 has a pin or roll 123 which is engaged by a cam formation 124 on the peripheral portion of the cam wheel 82, Fig. 4, the construction being such that upon rotation of the cam the clamps will be moved to and from operative position. A spring 125 interposed between a stop 126 and a collar 127 on the rod 120 serves to hold the roll 123 in engagement with its operating cam. To facilitate adjustment of the movement of the clamps, the rod 120 may be adjustable in length, as by a turnbuckle, as shown in Fig. 1.

Each operating arm 116, Fig. 3, has a slotted end portion 128 through which extends the sliding member or sleeve 112 which, as hereinbefore described, compresses the spring 115, Fig. 20, when the member or sleeve 112 is depressed, to effect a yielding clamping action of the clamp. As indicated in the sectional illustration of Fig. 20, the operating arm 116 normally rests upon the pin carrying lugs which project outwardly from the sleeve 112 and when the operating arm 116 is moved downwardly, it carries with it the sleeve 112, compresses the spring 115, and effects the downward, yielding clamping action of the clamp upon the upper. To insure the lifting movement of the clamp, the cap piece 113 may have associated therewith a collar 129, Fig. 20, provided with an outwardly extended portion 130 adapted to be engaged by the operating arm 116 as the latter is raised through the train of mechanism hereinbefore described. Adjustment of the cap piece 113 may be effected to vary the tension of the spring. While the means described for operating the clamps is found to be a good, practical form of this feature of the invention, yet variations may be made therein, it being desirable, however, that the clamps, as shown, be automatically operated to effect the clamping action upon the marginal portion of the upper and to release it at predetermined times, as will be more fully described.

Where the clamps, as in the construction shown, comprise plates such as 96, which extend continuously for some distance about the end portion of the shoe upper, it is sometimes desirable to connect the clamps at their ends to the operating arms, as well as at an

intermediate point such as hereinbefore described. To this end each operating arm 116 carries a sleeve 131, Fig. 15, which is confined to the arm 116 by a stop screw 132. Within the sleeve 131 is a plunger 133 upon which rests the lower end of a spring 134, the tension of which may be varied by a threaded adjusting cap 135. Against the plunger 133 rests the upper end of a pressure-transmitting member 136, the lower end of which is connected by a ball and socket joint 137 to the outer end portion of the clamp 96. The construction is such that when the operating arm 116 is moved downwardly to effect the clamping action upon the marginal portion of the upper, the outer end portion of the clamp will be moved downwardly under the yielding action of the spring 134 and insure, for example, a substantially equal clamping action on the marginal portion of the upper throughout the clamping surface of the clamp. On the other hand, it may be desired on some work to clamp the margin of the upper harder at some points than at others, for example to apply greater clamping pressure at the opposite sides of the form, at or near the location of the tip seam, than round the end of the form. This may be done in the construction shown by the independent means provided for adjusting the different springs 115 and 134.

When the form and the margin controlling means are relatively moved to lay the upper about the form, the clamps have a sufficient retarding action upon the withdrawal of the upper to insure its being drawn closely over the form. When, however, the wipers are operated to wipe the upper inwardly, and thus to lay the marginal portion of the upper over the bottom of the form, if the clamping pressure of the clamps were still maintained on the upper, or if the full force of such pressure were maintained, the wipers would be liable to injure or tear the upper, especially with some kinds of upper stock. Therefore the invention, in its illustrated embodiment, provides such an arrangement of wipers and clamps and their operating mechanism that during the time the upper is being laid about the form, the clamps will yieldingly retard the withdrawal of the upper; but before the wipers receive any substantial inward movement to wipe the marginal portion of the upper over the bottom of the form, the clamps will be caused by the cam 124 to release the upper substantially from clamping pressure. By reference to Fig. 17, however, it will be seen that the clamps do not receive at once their full withdrawing movement, but remain in position to bend the margin of the upper outwardly over the wipers while the wipers are closing, thus contributing to effectiveness of the wipers in wiping the upper smoothly and tightly inward over the form.

Substantially accurate conformation of the

upper with the surface of the form is essential to insure uniformity in the shape and condition of a line of shoe uppers molded about the form; and while the action of the clamps insures to a degree that the upper will be laid properly about the form, the invention further provides for working the upper heightwise of the form by pressure against the upper about the end of the form. This may best be effected by subjecting the portions of the upper which are about the lateral periphery of the form to the rubbing or wiping pressure of an embracing clamp or band, though other forms of means may suggest themselves within the scope of this feature of the invention. In the present instance band carriers 138 are guided for movement in slots 139 formed in the head portion 2 of the machine frame. The band carriers 138 carry the band support or backing 140, Fig. 6, comprising opposite side portions to which the band 141 is secured. The band may be of leather or other material suitable for the purpose. The band carriers are connected for pivotal swinging movement about an axis 142. Each of the band carriers 138 is under the influence of a spring which normally tends to separate the band carriers as indicated in Fig. 6. In the present instance the band carriers are provided with pins 143 to each of which is connected one end of a spring 144, the other end being secured at 145 to a fixed point in the machine, the construction being such that the springs 144 normally tend to open the end band.

Each of the end band carriers 138 has associated therewith an adjusting screw 146, Fig. 6, the rear end portion of which bears upon a sliding block or plunger 147 mounted for sliding movement in the head frame 2. Extending backwardly from the blocks 147 are links 148, the rear end portions of which are connected to the upper end portions of arms 149, Figs. 6 and 10, mounted upon a rock shaft 150. Extending from the rock shaft is an operating arm 151, Figs. 1 and 10, to which is connected an operating rod 152, Figs. 1 and 4, the lower end portion of which is connected at 153 to an arm 154 mounted for oscillating movement upon the support 19 and carrying at its outer end a cam follower or roll 155 which projects within a cam groove 156 formed in the face of the cam 82, the construction being such that as the cam rotates, the end band, which is indicated as a toe band, will be opened and closed as will more fully appear.

Since the end portions of shoe uppers will vary in size and shape in accordance with the size and style of shoes, provision is made in the present invention for accommodating the toe band to such variations. In the construction shown the pivotal connection 142, Fig. 6, between the end band carriers, is carried by a link 157 which in the closing and open-

ing of the band slides in a slot formed in the head frame of the machine and is pivotally connected at 158 to an operating lever 159 pivoted at 160 to a sliding carrier 161 which 5 is guided by a pin and slot guiding means 162 for endwise movement. The sliding carrier 161 is pivotally connected at 163, Fig. 10, to one of the arms 149 which operate the end band carriers, so that the band will be moved 10 lengthwise as well as opened or closed laterally. The end 164 of the lever 159 is connected to an adjusting rod 165 which has at its front end a threaded connection 166 with an adjusting nut 167. A spring 168 is interposed between a collar 169 on the adjusting rod 165 and the top frame 2 of the machine, the construction being such that the spring 168 normally forces the end 164 of the lever 159 rearwardly to position the pivotal 15 connection 142 of the end band carriers, and by adjustment of the stem 165 the initial position of this pivotal connection may be varied. Corresponding adjustments of the end band carriers about the axis 142 may be effected 20 by manipulating the screws 146. By these different means the band may be positioned to co-operate properly with different shapes and sizes of forms over which uppers are to be molded. By reference to Fig. 6 it 25 will be noted that the link 157 is permitted to have a limited lateral movement in the slot through which it extends, and provision is thus afforded for bodily lateral movement of the band in one direction or the other to accommodate 30 itself to the form as the latter is forced downwardly within it. It will be evident that the band carriers are unyieldingly positioned against lateral swinging movement and against movement lengthwise 35 of the form in response to the forming pressure, thus maintaining the band in unvarying contour throughout the upwiping operation.

The form 170, Figs. 7, 8 and 9, has a forming 40 surface corresponding substantially to the shape that the shoe upper is to have in the finished shoe; and on its bottom face a marginal edge shoulder 171 extending inwardly a short distance from the outer edge 45 of the form. At the inner portion of the shoulder 171 the form is provided with a raised portion or shoulder 172, the construction being such that when the upper is wiped in by the wipers it will be laid upon the shoulder 50 171 of the form to provide an inwardly-extending shoulder on the upper, and the edge portion of the upper will be compressed or molded about the central raised portion of the form to provide an upstanding marginal 55 flange.

In the present instance the form 170 is mounted upon the form carrier 47 and is preferably detachably connected thereto. As shown, the form has in its bottom, which 60 is uppermost, a hollowed portion 173, Figs.

7 to 9, and an inwardly-extending flange 174 beneath which is adapted to engage a collar 175 formed on the lower end of a form-securing rod or stem 176. The upper end portion of the securing rod is provided with a screw 70 thread 177, which is engaged by an adjusting nut 178. The rod 176 extends through a bushing 179, the lower end portion of which is formed with a shoulder 180 adapted to engage the top surface of the flange 174 extending inwardly in the recess 173 of the form, the construction being such that when the flange 174 is placed between the collar 175 and the shoulder 180 of the bushing, and the adjusting nut 178 is manipulated, the form will be 80 secured in operative position on the form carrier. The described detachable connection between the form and the form carrier presents a convenient and ready means for effecting a change in forms, but the particular 85 means may be varied.

As the upper is molded about the form, the latter is subjected to an endwise pressure outwardly or toward the heel end of the upper. The present invention provides additional 90 means for counteracting such pressure against the form by a brace adjustably connected to the form carrier. In the construction shown a brace or abutment 181, Figs. 1 and 7, is pivotally mounted at 182 between arms 183 95 on the form carrier 47. The lower end portion of the brace 181 is provided with a lug 184, the inner face of which, when the brace is in bracing position, bears against the front end face 185 of the form. An adjusting 100 screw 186 bears against the end of a hardened plug 187 in the form carrier, and serves as a means for varying the bracing effect of the brace.

In forming or molding the end portions of 105 shoe uppers where the stiffener is made pliable by heat, it is sometimes desirable that the end of the upper be subjected to the action of a softening heat during molding, sufficient to permit the stiffener to be molded into close 110 conformation with the form. In the present instance the form may be heated by one or more heat units. In the construction illustrated two such heat units 188, Fig. 9, are indicated. These extend into a suitable cavity 115 made in the form and are connected to wires 189 which may be conveniently directed along the form carrier 47.

While the upper is being subjected to the 120 upwiping action of the end band and being laid or stretched about the form under the tensioning action of the clamps and wipers, the uniformity of the final product demands that the upper be held from displacement on the form; and one of the features of the present invention has this in view. In the present instance there is provided an abutment or pad to engage the top or intermediate portion of the toe end of the upper and between which and the form the upper is held during 125 130

the operation of conforming the upper to the form. Adjustably mounted in the head portion of the machine frame is an arm 190, Fig. 1, which may be secured in position by a set 5 screw 191. The arm 190 carries a casing 192 in which is mounted a plunger 193, Figs. 1 and 11, normally held in an upward position by a spring 194 within the casing, the upper end of the spring bearing upon the plunger 193, and the lower end resting upon an adjustable sleeve 195, whereby the action of the spring in transmitting pressure to the plunger 193 may be varied. The spring 194 may be 10 suitably held in place by a rod 196 secured to the plunger 193 and extending loosely through the adjusting member 195. Turning movement of the plunger is prevented by a lug 197 which projects within a slot 198 in the casing, and its upward movement is limited by engagement of a nut on the end of the 15 rod 196 with the member 195.

Pivottally connected to the top of the plunger 193 at 199, Figs. 1 and 16, is the rest 200 which carries a pad 201 having a surface 25 corresponding to the contour surface of the opposed portion of the form. Springs 202, Fig. 16, normally hold the rest 200 in a pre-determined horizontal position with provision 30 for tilting movement to conform to the surface engaged by the pad. The construction is such that the unconfined portion of the upper is depressed by the form into engagement with the pad 201 which, under the action of the spring 194, assists in preventing 35 displacement of the upper relatively to the form as the upper is being laid and wiped about the form.

When the upper has been molded about the form, it is permitted to remain in molded position on the form for a considerable length 40 of time to afford an opportunity for the upper to set in the permanent shape it is to have in the finished shoe. If, during this time, the end band remained in pressing contact 45 with the upper, it would be liable to mark the surface of the upper, due in part to the softened condition of the end stiffener. The present machine provides for relaxing or 50 removing the pressure against the upper while it is permitted to set; and to this end the mechanism for operating the end band is so constructed and arranged as to relieve 55 the pressure of the band soon after the upper has been fully laid about and wiped into conformation with the form, as represented in Fig. 19.

The machine is further provided with 60 means for trimming the upstanding marginal flange of the upper about the toe end while the upper is under control of the molding means, to prepare this portion of the upper for the inseam sewing operation. The trimming means in the construction shown is associated with the form, and is supported in 65 position to trim the upper substantially in

the plane of the top surface of the wipers when they are in their inner position and are holding the upper. The trimmer may be variously constructed but in the present instance it is formed as a blade 203, Figs. 7 and 8, carried by a sleeve 204 rotatable about 70 the stem 176 and supported in such position that the surplus upper stock wiped in by the wipers will be brought into the field of action of the trimmer. The sleeve 204 is mounted on the lower end portion of the bushing 179 and is power operated at times for effecting the trimming operation. Mounted upon the bushing 179 above the sleeve 204 of the trimmer is a pinion 205 which is in operative engagement with a pinion 206 mounted on a shaft 207 extending through a suitable bearing formed in the form carrier 47. At its upper end the shaft 207 is provided with a pinion 208 which is engaged by the teeth of 85 a rack 209, Fig. 7, receiving reciprocating movements at the desired times for operating the trimmer through a train of mechanism operated by a cam on the sleeve 28. In the present instance the rack 209 is connected by 90 a link 210, Fig. 1, to an arm 211 pivotally mounted at 212 upon the form carrier 47. Connected to the arm 211 is a downwardly-extending arm 213 which is connected by a link 215 to a bell-crank lever 214. The bell-crank lever 214 has connected to it at 216 an operating rod 217, the lower end portion of which is adjustably connected to a cam 95 operated arm 218 mounted upon the support 54. The arm 218 is provided with a cam 100 follower or roll 219 which travels in a cam groove 220, Fig. 4, formed in the face of the cam wheel 82, the construction being such that the rack 209 will be reciprocated by rotation of the cam to impart to the trimmer 105 its operating movements.

When the end of the shoe upper has been molded to the shape which it is to have in the finished shoe, the shoe is to be lasted. During the lasting operation, it is desirable to subject 110 the upper to a lasting pull at the tip line or where the tip is secured to the vamp. Therefore the trimming means as herein shown is constructed and arranged to make a trimming cut from a point in front of the tip seam at 115 one side of the end of the upper to a point in front of the tip seam at the opposite side; and since the size, form, and relation of the tip to the vamp may vary in different styles and sizes of shoes, provision is made for adjusting 120 the trimming means to effect its described purpose upon shoe uppers of different sizes and styles. This may be variously effected, but in the present instance the arm 218 for 125 operating the trimmer is provided with an end portion having a series of openings 221 to which the lower end of the operating rod 217 may be selectively connected, the effect being that the trimmer will be given movements of greater or less amplitude. The point where 130

- the trimmer terminates its cutting movement may thus be varied to correspond to the requirements of different styles and sizes of shoe uppers, as indicated for example by Figs. 24 and 25 where the cutting movement of the knife ends at 224 and 226 respectively, in front of the tip seam 223. A corresponding variation with respect to the point (222 or 225) where the knife begins its cut at the opposite side of the upper may be effected, when necessary, by substituting a knife of different length, the machine being so constructed that different knives may be readily substituted. The knife is adapted to trim the upper as required by a single cutting movement, but it is immediately returned to its starting position, and for further effectiveness in making a clean cut along the margin of the upper it is provided with cutting edges on its opposite sides. It will be evident that the trimming knife in the construction shown cuts in a single plane and does not sever from the upper the rear ends of the band of waste material which it trims off round the toe. This avoids all danger of clogging or otherwise interfering with the operation of different parts of the machine by the accumulation of scrap material. After the upper has been removed from the machine the band of material which has been trimmed off round the toe may be severed from the upper by the use of a hand knife or by other convenient means.
- The upper stock will vary in thickness, and since the trimmer is to trim the upstanding flange of the upper in the plane of the upper surface of the wipers, means are provided to insure that the trimmer will operate to trim the stock in the desired relation to the wipers, regardless of variations in the thickness of the stock and consequent variations in the position of the form after the upper has been wiped in by the wipers and after the form has been pressed yieldingly upward. In the present instance the sleeve portion 204 of the trimmer is provided with a circular groove 227, Figs. 7 and 8, which is embraced by an arm 228 removably secured in a head 229 on the end of a carrier 230, Figs. 1 and 7, mounted on the pivotal support 46 of the form carrier 50 at 231. The head 229 is connected to a stem 232, Fig. 7, which extends upwardly through the form carrier with a sliding fit, suitable stops such as nuts 233 being provided to adjustably limit the downward movement of the head 229 under the action of a spring 234 interposed between the carrier 47 and the top portion of the head 229. Mounted in the cover plate 61 which overlies the wiper holders 62 is an adjustable stop 235 which is adapted to be engaged by a lug 236 carried by the head 229 when the form carrier 47 is moved downwardly to lay the upper about the form. The construction is such that when the form and the wipers are relatively moved to lay the upper about the form and to compress its mar-

ginal portion between the form and the wipers, the cutting plane of the trimmer is automatically determined irrespective of the position of the form.

In order to permit the trimmer to be readily removed when desired, the arm 228, Fig. 7, is made detachable from its connection with the trimmer by means of a spring clip 237. Upon lifting the clip 237, the arm 228 may be moved backwardly in the head 229 and disengaged from the trimmer, whereupon the thumb nut 178 may be loosened to permit detachment of the form and subsequent removal of the trimmer.

When the end of a shoe upper has been formed and trimmed, as hereinbefore indicated, it is liable to stick or adhere to the form after the upper has set; and to meet this condition the present invention provides for detaching the finally shaped and molded end of the upper from the form. In the present instance a detacher is provided, consisting of a stem or plunger 238, Figs. 8 and 9, having a headed portion 239 normally held retracted in a slot formed in the end portion of the form by means of a spring 240 interposed between the surface 185 of the form and a head 241 on the plunger, the construction being such that after the end of the upper has been molded and set to the form and the form has been moved to its inoperative position, a push upon the head 241 of the plunger will serve to move the molded end of the shoe upper endwise of and detach it from the form. To avoid interference with the lower end of the stem 176 which co-operates to hold the form on the form carrier, the lower end portion of the stem 176 is slotted from its bottom surface upward and the stem or plunger 238 extends through such slotted portion.

A shoe upper formed in accordance with the present disclosure and adapted more particularly for welt shoes, is shown in Fig. 26, wherein it will be seen that the toe end of the upper is molded or formed to the final shape it is to have in the finished shoe, and is provided with an upwardly extending marginal flange 243 of a height substantially corresponding to the height of the lip of the insole to which it is to be attached, the trimmed portion of the flange terminating preferably at points in front of the tip line to provide adjacent to the tip line the extensions 244 for use during the lasting operation. The flange 243 as thus molded is in position to lie in close conformity to the rib of the corresponding shoe insole and extends upwardly from a portion which is molded over the surface 171 of the form to lie on the feather of the insole.

In the use of the machine shown, the workman positions the inverted upper on the presenter by engaging the end portions of the presenter with the jig holes in the upper, as shown in Fig. 23, and then moves the presenter to carry the upper into operative rela-

tion to the form. In doing this he moves the pins on the presenter into the slots 85 in the wipers until the pins interlock with the offset portions 94 of the slots, and when the presenter has finally reached the position thus predetermined by the positioning slots in the wipers, the shoe upper assumes a predetermined position relatively to the form. This condition is represented in Fig. 11, at which time it will be noted that the clamps 96 are in their raised or open position. The workman thereupon treadles the machine, the first effect of which is that the clamps descend and engage the marginal portion of the upper and press it yieldingly against the top surface of the wipers, and at the same time press downwardly upon the holding pins of the presenter and assist the operator in effecting its detachment from the upper, the ends of the pins being preferably somewhat rounded to permit them to slip out readily when they are pushed down. The upper is then positioned in the machine and held in its predetermined relation to the form between the clamps and the wipers. During the downward movement of the clamps, the links 103 move them also inwardly to bring their edge portions in close proximity to the edge portions of the wipers, substantially as represented in Fig. 13. The end band is at this time in its closed position, ready to act with wiping pressure upon the upper toward the bottom of the form. The form thereupon is moved downwardly upon the unconfined portions of the end of the upper and the toe pad 201 engages and holds the upper from displacement about the form. As the form continues to descend, the marginal portions of the upper are partially withdrawn from the confining means or clamps, the upper is laid about the form with an upper stretching pull, and the end band simultaneously acts to wipe or work the upper heightwise about the end of the form, substantially as indicated in Fig. 16. The downward movement of the form is continued until the shouldered portion 171 of the form is slightly below the lower surface of the wipers, whereupon the wipers are automatically moved inwardly to gather and lay the upper over the bottom of the form and to mold it into an upstanding flange against the shoulder 172. Prior to any substantial inward movement of the wipers the clamps are automatically operated to relieve the marginal portions of the upper from clamping pressure, substantially as indicated in Fig. 17. After the wipers have wiped in the marginal portions of the upper, and while the upper is still held between the form and the rest 201 and subjected to the pressure of the end band, the form is slightly raised under the action of the spring 58, Fig. 1, to press the upper firmly against the bottom surface of the wipers, whereupon the trimmer is automatically operated to trim the upstanding margin of the upper while it is securely held to the form, as indicated in Fig. 18. The end band is then automatically moved outwardly from the end and the sides of the form to remove its pressure from the upper and to permit the upper to set, without marking the upper, substantially as indicated in Fig. 19. The machine then comes to rest automatically at the completion of the above series of operations. After a sufficient lapse of time to permit the upper to set to the final shape it is to have in the finished shoe, during which time an upper may have been presented and molded in the other portion of the machine, the workman again treadles that part of the machine in which the first upper was molded, whereupon the wipers move outwardly and the form rises carrying the end of the shoe upper, which may be detached from the form by the detacher. Just prior to the conclusion of the second portion of the cycle of operations, the end band is moved inwardly so that at the beginning of another operation for molding the end of a shoe upper the band will be in position to effect its upwiping and rubbing pressure upon the upper.

Certain novel method aspects of the procedure hereinbefore set forth, relating especially to the presentation of the work to the operating means and to the trimming of the upper, are covered by claims in a divisional application Serial No. 134,711, filed on September 10, 1926. Furthermore, in respect to the jiggling of the upper, the organization herein shown and described is constructed to carry out a method claimed in a copending application of George E. Warren, Serial No. 476,659, filed on June 11, 1921.

Having described the invention, what I claim as new and desire to secure by Letters Patent of the United States is:

1. In a machine for shaping parts of shoes, the combination with means for applying pressure to a shoe part to give it substantially the shape which it is to have in the finished shoe, of positioning means comprising a member for engaging the shoe part in a jig hole formed in said part outside of the area where the shaping pressure is applied to position the part for the operation of the pressure applying means.
2. In a machine for molding shoe parts, the combination with molding means comprising a form, of means for engaging a shoe part in a plurality of jig holes in said part located at its opposite sides respectively outside of the area where the molding pressure is applied to jig the part in relation to the form.
3. A molding machine having, in combination, means for molding a shoe part to give it substantially the shape which it is to have in the finished shoe, means for jiggling the shoe part to position it for the operation of said

- molding means, and means for trimming said part while it is under control of the molding means. 65
4. In a machine for use in the manufacture of shoes, the combination with means for molding a shoe part, of means for jiggling a shoe part in relation to said molding means comprising a device for engaging said part in jig holes formed therein and for moving it 10 into jigged position and for then disengaging said part to leave it in jigged position. 70
5. In a machine for use in the manufacture of shoes, the combination with means for molding a shoe part, of positioning means comprising a member for engaging a shoe part in a jig hole formed in said part inside of its marginal edge to position the part in relation to said molding means, said member being movable out of the jig hole to 15 leave the shoe part in the position thus determined. 75
6. In a machine for use in the manufacture of shoes, the combination with means for operating upon a shoe part, of means for jiggling a shoe part in relation to said operating means comprising jig pins movable laterally to position said part while engaging it in jig holes formed therein and then movable lengthwise out of said jig holes to leave the part in 20 jigged position. 80
7. In a machine for use in the manufacture of shoes, the combination with means for operating upon a shoe part, of means for jiggling a shoe part in relation to said operating means comprising a jig pin movable laterally to present said part while engaging it in a jig hole formed therein, and means for engaging said pin to determine the position in 25 which the part is presented. 85
8. In a machine for use in the manufacture of shoes, the combination with means for operating upon a shoe part, of a presenter movable manually to present a shoe part in a relation to said operating means determined by engagement of the presenter with a portion of 30 the machine and then to withdraw from the shoe part to leave it in the position thus determined. 90
9. In a machine for use in the manufacture of shoes, the combination with means for operating upon a shoe part, of means for jiggling a shoe part in relation to said operating means comprising a presenter constructed to engage jiggling surfaces on the shoe part and 35 to be manipulated by the operator to effect a manual presentation of said part to the means for operating upon it, and means co-operating with said presenter to determine the position in which the shoe part is thus presented. 95
10. In a molding machine, the combination with means for molding a shoe part, of a presenter constructed to engage a shoe part in jig holes formed in said part, said presenter comprising a tool for use by the operator to 40 engage and support the shoe part and present it to the molding means, and means for engaging the presenter to determine the position in which it presents the shoe part for the operation of the molding means. 100
11. In a molding machine, the combination with means for molding a shoe part, of means for engaging jiggling surfaces on a shoe part and for moving the part by such engagement into jigged relation to the molding means. 105
12. In an upper shaping machine, the combination with upper shaping means, of means for engaging positioning surfaces formed on an upper in proximity to its marginal edge and for positioning the upper by such engagement with respect to movement in different directions lengthwise and transversely of its edge relatively to the upper shaping means. 110
13. In an upper shaping machine, the combination with a form, and means for shaping an upper over the form, of means for engaging the upper in jig holes provided therein to position it relatively to the form. 115
14. In an upper molding machine, the combination with means for molding an end portion of an upper to give it substantially the shape which it is to have in the finished shoe, of means for jiggling the upper in relation to said molding means comprising members for engaging the upper in jig holes formed in its margin at opposite sides of its end portion. 120
15. A molding machine having, in combination, a toe form, means co-operating with said form to mold material substantially in the shape of a shoe toe, and members for engaging the material in jig holes formed in said material to position the material for the molding operation. 125
16. In a machine for shaping the toes of uppers, the combination with upper shaping means, of means for fixing the longitudinal, lateral and angular relation of the toe of an upper to said upper shaping means comprising members for engaging the upper in jig holes at opposite sides of the toe and means for determining the locations of said members relatively to the upper shaping means. 130
17. A machine of the class described having, in combination, toe molding means constructed and arranged to receive the toe portion of assembled upper materials in position for molding, and means for jiggling the upper materials in relation to said molding means comprising members arranged to enter jig holes formed in said materials at opposite sides of the toe substantially in the location of the tip seam. 135
18. In an upper shaping machine, the combination with upper shaping means, of means for jiggling an upper in relation to said upper shaping means comprising members arranged to engage the upper in jig holes formed in the 140

- upper, said members being movable out of the jig holes to leave the upper in jigged position. 65
19. In a machine for molding uppers, the combination with means for molding an upper over a form before the upper is fastened to a sole, of a member constructed for use manually to present an upper to the molding means and then to withdraw from the upper to permit the molding operation to be effected. 70
20. In a machine of the class described, the combination with a form, and means for shaping an upper over the form, of means for engaging jigging surfaces on the upper and for moving the upper while thus engaged into jigged relation to said form. 75
21. In an upper molding machine, the combination with means for molding an end of an upper, of a tool constructed to support an upper and to engage positioning surfaces at opposite sides of an end of the upper to determine the relation of the upper to the tool, said tool being adapted for use manually to present the upper in position for said end to be molded. 80
22. In a machine of the class described, the combination with upper shaping means, of a member constructed to engage positioning surfaces on an upper to determine the relation of the upper to said member and adapted for use manually to present the upper to the upper shaping means, and means co-operating with said member to determine the position in which the upper is presented. 85
23. In a machine of the class described, the combination with means for molding an end portion of an upper, of a jigging tool constructed to enter jig holes in the upper and to be manipulated by the operator to present the upper to the molding means, and means co-operating with said jigging tool to determine the position in which the upper is presented. 90
24. In a machine of the class described, the combination with means for molding an end portion of an upper, of a presenter adapted for use as a hand tool and having pins arranged to enter jig holes formed in the upper, and means for engaging said pins to locate the presenter and the upper relatively to the molding means. 95
25. In a machine of the class described, the combination with means for molding an end portion of an upper, of a presenter having pins to enter jig holes at opposite sides of the upper and movable to present the upper to the molding means, and means constructed to interlock with said pins to determine the lengthwise and lateral position in which the upper is presented. 105
26. In a machine of the class described, the combination with upper molding means, of a presenter constructed for use manually to present an upper to said molding means, and means for guiding said presenter into predetermined relation to the molding means. 110
27. In a toe molding machine, the combination with toe molding means, of means for engaging an upper in jig holes formed in proximity to the marginal edge of the upper at opposite sides of the toe and for positioning the upper by such engagement with its toe portion outspread for the operation of the molding means. 115
28. In a toe molding machine, the combination with a form, of means for clamping the marginal portion of toe material in a predetermined position relatively to the form, and a presenter for presenting toe material to said clamping means, said presenter and clamping means being constructed for interengagement to determine the position in which the material is presented. 120
29. In a machine for shaping the toes of uppers, the combination with means for clamping the marginal portion of the toe of an upper for the upper shaping operation, of members for engaging the upper in jig holes formed in its margin at opposite sides of the toe and for presenting the upper to the clamping means, said clamping means having guide slots to receive said members and determine the position in which the upper is presented. 125
30. In a machine for molding the toes of uppers, the combination with a form, of wipers for wiping an upper inwardly over the form, said wipers having portions constructed to co-operate with an upper presenting member to determine the relation to the form in which the upper is presented. 130
31. In a machine for molding the toes of uppers, the combination with a form, of wipers for wiping an upper inwardly over the form, and a presenter for engaging an upper and moving it into position for the toe molding operation, said wipers having guide slots to receive said presenter and determine the relation to the form in which the upper is presented. 135
32. In a machine for molding the toes of uppers, the combination with a form, of wipers for wiping an upper inwardly over the form, and a presenter having projections arranged to engage the upper in jig holes at opposite sides of the toe and adapted for use by the operator to present the upper in position for molding, said wipers having slotted portions constructed to interlock with said projections to determine the angular relation to the form in which the upper is presented. 140
33. In a machine for molding the toes of uppers, the combination with a form, of wipers for wiping an upper inwardly over the form, and a presenter constructed to present the upper with its margin overlying the wipers, said presenter having portions arranged to engage the wipers on the opposite side from the upper to guide it in presenting the upper. 145

34. In a machine for molding the toes of uppers, the combination with a form, of wipers for wiping an upper inwardly over the form, said wipers having slots in their front end portions, and a presenter having projections adapted to engage an upper in jig holes at opposite sides of its toe portion and to enter said slots, said presenter having ledges to underlie the wipers and guide it in presenting the upper.

35. A presenter for presenting an upper to means for operating upon the upper, comprising members arranged to extend along the opposite sides of the upper to support the upper in inverted position and having projections arranged to engage the upper in jig holes formed in its opposite side portions.

36. A presenter for presenting an upper to means for operating upon the toe of the upper, comprising opposite side portions spaced to receive the upper between them and adapted to support the upper in inverted position and end portions constructed to engage the upper at opposite sides of the toe and to hold the toe outspread.

37. A presenter for use in presenting an upper manually to means for operating upon the toe portion of the upper, comprising pins arranged to engage the upper in jig holes formed at opposite sides of its toe portion and members extending from said pins along the sides of the upper to the rear of its heel end portion to provide a handle for use by the operator in presenting the upper.

38. A presenter for use in presenting an upper to means for operating upon the toe of the upper, comprising portions spaced laterally and provided with projections for engagement with the upper in jig holes formed at opposite sides of the toe to position the toe of the upper outspread, said presenter having also portions arranged relatively nearer together for engagement with opposite sides of the upper at the rear of the toe to support the upper in inverted position and an extension adapted to serve as a handle for use by the operator in presenting the upper.

39. A presenter for use in presenting uppers to means for operating upon said uppers, comprising a looped member having on its opposite side portions projections for engagement with each upper in jig holes formed at opposite sides of the upper, said member being resilient to adapt it for engagement with uppers of different shapes and sizes.

40. In a machine of the class described, the combination with means for operating on shoe material to give it substantially the shape desired for the finished shoe, of means for jiggling the material to position it relatively to said operating means comprising a member for engaging the material in a jig hole formed therein, and means for imparting to said member movement in a direction

to withdraw it from the jig hole to free the material for the action of said operating means.

41. In an upper shaping machine, the combination with upper shaping means, of a presenter constructed to engage an upper in predetermined relation to the upper and movable to present the upper to the upper shaping means, and means for imparting to said presenter movement in a direction to disengage it from the upper to free the upper for the shaping operation.

42. In an upper shaping machine, the combination with a form, of means for jiggling an upper in relation to said form comprising pins arranged to project in jig holes in the upper, and means for shaping the upper over the form and for moving said pins in a direction to withdraw them from the jig holes.

43. In an upper shaping machine, the combination with power operated upper shaping means, of a presenter constructed to engage an upper in jig holes formed in the upper and adapted for use manually to present the upper in predetermined relation to said upper shaping means, and means automatically operative in time relation to the upper shaping means to impart to said presenter movement in a direction to disengage it from the upper.

44. In a machine of the class described, the combination with means for jiggling shoe material comprising a member arranged to enter a jig hole in the material, of means for clamping the material automatically operative in the clamping operation to engage said member and move it in a direction to withdraw it from the jig hole.

45. In a machine for molding the toes of uppers, the combination with a form, of means for jiggling an upper in relation to said form comprising members for engaging the upper in jig holes provided in the margin of the upper at opposite sides of the toe, and clamping means arranged to clamp the margin of the upper and to impart to said members in the clamping operation movement in a direction to disengage them from the upper.

46. In an upper molding machine, the combination with upper molding means, of a presenter constructed for engagement with an upper in jig holes formed in the upper and movable to present the upper for the molding operation, and means for engaging said presenter to determine the longitudinal, lateral and angular relation of the upper to the molding means.

47. In an upper shaping machine, the combination with means for clamping the marginal portion of the toe of an upper for the upper shaping operation, of means for jiggling the toe of the upper to fix its relation to said clamping means comprising members

- for engaging the upper in jig holes formed in its margin at opposite sides of the toe.
48. In an upper shaping machine, the combination with a form, of means for jigging an upper in relation to said form, means for clamping the upper in its jigged position, and means for thereafter shaping the upper about the form.
49. In an upper shaping machine, the combination with a form, of means for jigging an upper to fix the relation of its marginal portion to said form, and means for clamping the marginal portion of the upper thus jigged and for shaping the upper about the form.
50. In an upper shaping machine, the combination with a form, of means for jigging an upper in relation to said form by engagement with the upper in jig holes formed in the marginal portion of the upper, a device for clamping the marginal portion of the upper in its jigged position, and means for operating said clamping device to clamp the upper and for then effecting relative movement of the clamping device and the form to lay the upper about the form.
51. In an upper shaping machine, the combination with a form, of means for jigging an upper in relation to said form, means for clamping the upper against the form to hold the upper from displacement, and means for shaping the upper over the form while it is clamped against the form.
52. In an upper shaping machine, the combination with a form, of jigging means for engaging the upper temporarily in jig holes provided in the upper to fix its relation to the form, means for clamping the upper against the form to hold it from displacement and permit the withdrawal of the jigging means, and means for shaping the upper over the form after the jigging means has been withdrawn.
53. In a machine for shaping the toes of uppers, the combination with a form, of means for jigging an upper in relation to said form by engagement with the upper in jig holes in its margin, means for clamping the marginal portion of the toe of the upper thus jigged, additional means for clamping the top of the toe portion of the upper against the form, and means operative while the upper is thus clamped against the form to shape the upper over the form while partially withdrawing the margin of the upper from its clamping means.
54. In a machine for shaping the toes of uppers, the combination with a form, of means for jigging an upper in relation to said form, means for clamping the marginal portion of the toe of the upper thus jigged, means for thereafter effecting relative movement of said clamping means and the form to lay the upper about the form, and a member arranged to clamp the top of the toe portion of the upper upon the form to assist in holding the upper against displacement as it is laid about the form.
55. In an upper shaping machine, the combination with a form, of means for jigging the toe end portion of an upper outspread in relation to said form, a device for clamping the marginal portion of the toe of the upper thus positioned, a toe pad for engaging the top face of the toe portion of the upper, and means for operating said form to press the upper upon said toe pad and thereafter to move said toe pad with the form relatively to the clamping device to lay the upper about the form.
56. In an upper shaping machine, the combination with a form and wiping means relatively movable to wipe an upper heightwise of the form, of means for engaging the upper in jig holes provided in its marginal portion to fix the relation of the upper to the form prior to the wiping operation.
57. In an upper shaping machine, the combination with a form, of means for jigging an upper in relation to said form, means for clamping the upper in its jigged position, and means for thereafter wiping the upper about the form toward the edge of the bottom face of the form.
58. In an upper shaping machine, the combination with a form, of means for jigging the toe end portion of an upper in relation to said form, means for clamping the top of the toe portion of the upper against the form to hold the upper and permit withdrawal of the jigging means, and means for wiping the upper about the form toward the edge of the bottom face of the form while the upper is thus clamped and after the jigging means has been withdrawn.
59. In an upper shaping machine, the combination with a form, of means for jigging the toe end portion of an upper in relation to said form, a toe pad for engaging the top face of the toe portion of the upper, operating means for moving the form to press the upper upon said toe pad and for thereafter moving the form and the toe pad together heightwise of the form, and a toe embracing member arranged to act in such movement of the form to wipe the upper toward the edge of the bottom face of the form.
60. In an upper shaping machine, the combination with a form, of manual means for moving an upper into predetermined relation to said form, and power means automatically operative upon the starting of the machine to assume control of the upper and to shape the upper over the form.
61. In an upper shaping machine, the combination with a form, of means constructed for use manually to jig an upper in relation to said form, and power means automatically operative upon the starting of the machine to clamp the upper in its jigged position and then to shape the upper over the form.

62. In an upper shaping machine, the combination with a form, of a presenter constructed for engagement with an upper in jig holes formed in the upper and adapted for 5 use manually to present the upper to the form, means for engaging said presenter to determine the position in which the upper is presented, and power operated means for engaging the upper thus presented and for 10 shaping it over the form. 63. In an upper shaping machine, the combination with means for operating upon an end portion of an upper to give it substantially the shape which it is to have in the 15 finished shoe, of means for jiggling the upper in relation to said upper shaping means, and means for trimming the end portion of the upper while it is under control of the upper shaping means. 64. In an upper shaping machine, the combination with a form, of means for jiggling an upper to fix its relation to the form, means for shaping the upper over the form, means for trimming the upper while it is on the form, 20 and means for clamping the upper against the form to hold it for the upper shaping and trimming operations. 65. In a toe molding machine, the combination with a form, of means for jiggling the 30 toe end portion of an upper in relation to said form, means for molding the upper over the form to produce an upstanding marginal flange, and means for trimming said flange while the upper is on the form. 66. An upper shaping machine having, in combination, means for jiggling an upper in substantially inverted position by engagement with the upper in jig holes formed in the upper, and upper shaping means relatively to which the upper is thus jiggled for 35 operating upon a portion of the upper in said position to give it substantially the shape which it is to have in the finished shoe. 67. An upper shaping machine having, in combination, means for presenting an upper in substantially inverted position comprising a presenter constructed to support the upper in that position and having members arranged to enter jig holes formed in the opposite side 40 portions of the upper, a form mounted in substantially inverted position and relatively to which said presenter is movable to present the upper, and means co-operating with said form to shape the upper thus presented. 68. An upper shaping machine having, in combination, means for jiggling the toe end portion of an upper in substantially inverted position comprising jig pins arranged to project upwardly in jig holes formed in the margin of the upper at opposite sides of its toe portion, a form mounted in substantially inverted position and relatively to which the upper is thus jiggled, and means for operating 45 upon the upper in said position to shape its toe end portion over the form. 69. In an upper shaping machine, the combination with upper shaping means comprising a form over which to shape an upper, of a device constructed to support assembled upper materials in substantially inverted position and movable to present said materials in predetermined relation to said form. 70. In an upper shaping machine, the combination with a form over which to shape the toe end portion of an upper, of means for clamping the marginal portion of the toe end of the upper, operating means for effecting relative movement of said clamping means and the form to lay the upper about the form, means for embracing the toe of the upper and wiping it heightwise of the form, said wiping means being rigidly supported against alteration of its contour in the wiping operation, and a device for engaging the top of the upper and pressing it against the form to hold it from displacement as it is shaped over the form. 75 80 85 90 95 100 105 110 115 120 125 130
71. In an upper shaping machine, the combination with a form over which to shape the toe end portion of an upper, of a band for wiping the upper over the form toward the edge of the bottom of the form, means for maintaining said band in unvarying contour in the wiping operation, and clamping means arranged to clamp the top of the toe portion of the upper against the form as the upper is wiped over the form. 72. In an upper shaping machine, the combination with a form over which to shape the toe end portion of an upper, of a wiping member for embracing the upper and wiping it over the end and side faces of the form, means for moving the form relatively to said member to wipe the upper while maintaining said member substantially stationary throughout the wiping operation, and a spring controlled toe pad yieldable in response to such movement of the form for clamping the upper against the form with increasing pressure as the wiping operation proceeds. 110 115 120 125
73. In an upper shaping machine, the combination with a form over which to shape the toe end portion of an upper, of wipers for wiping the marginal portion of the upper inwardly over the bottom of the form, means for clamping the marginal portion of the upper upon said wipers, means for effecting relative movement between the form and said wipers and clamping means in time relation to the clamping of the upper to lay the upper about the form, and additional means for wiping the upper over the end face of the form to conform it to the contour of said face. 115 120 125
74. In a toe molding machine, the combination with a toe form, of wipers for wiping the marginal portion of an upper inwardly over the bottom of said form, means for clamping the marginal portion of the upper upon said wipers comprising clamping plates relatively to which the upper is per-

- mitted to slip, means for effecting relative movement between the form and said wipers and clamping plates to lay the upper about the form and partially to withdraw the upper from between said plates and the wipers, and a wiping band for embracing the upper about the form, said band being automatically operative to wipe the upper heightwise of the form as it is laid about the form.
75. In a toe molding machine, the combination with a form over which to mold the toe of an upper, of end embracing wipers, means for clamping the marginal portion of the upper on said wipers, power operated means for effecting relative movements in time relation between said form and the wipers and clamping means to draw the upper over the form and to wipe its margin inwardly over the bottom of the form, and a device automatically operative to wipe the upper heightwise of the form before it is wiped inwardly over the bottom of the form.
76. In a toe molding machine, the combination with a form over which to mold the toe of an upper off the last, of means for supporting said form by its bottom portion, means for wiping the upper heightwise of the form, and additional means for wiping the upper inwardly over the bottom of the form to mold a marginal flange on the upper.
77. In a toe molding machine, the combination with a form over which to mold the toe of an upper off the last, of means for supporting the form from above in inverted position, a wiping member for embracing the upper about the form and for wiping it over the end and side faces of the form, end embracing wipers, and means for operating said wipers to wipe the marginal portion of the upper inwardly over the bottom of the form to mold a marginal flange on the upper.
78. In a toe molding machine, the combination with a toe form, of means for supporting said form by its bottom portion to permit assembled upper materials to be removed from the form while the form is in the machine, a device for wiping the upper heightwise of the form, power operated means for effecting relative movement between said device and the form to wipe the upper, and power means for wiping the marginal portion of the upper inwardly over the bottom of the form after the upper has been wiped heightwise of the form.
79. In a toe molding machine, the combination with a toe form over which to mold the toe of an upper off the last, of means for wiping the upper heightwise of the form and for then clamping it against the end and side faces of the form, and automatic means for wiping the marginal portion of the upper inwardly over the bottom of the form while the upper is thus clamped.
80. In a toe molding machine, the combination with a form over which to mold the toe of an upper off the last, of a toe embracing band, operating means for moving the form relatively to said band to cause the band to wipe the upper heightwise of the form, a toe pad yieldable in response to such movement of the form for clamping the top of the forepart of the upper against the form, and end embracing wipers for thereafter wiping the marginal portion of the upper inwardly over the bottom of the form.
81. In an upper shaping machine, the combination with end embracing wipers and means for operating them to wipe the marginal portion of the toe of an upper inwardly over a form, of means for clamping the margin of the upper and for shaping the upper over the form prior to the operation of said wipers, and means automatically operative to relax the clamping pressure on the margin of the upper prior to any substantial inward movement of the wipers.
82. In a toe molding machine, the combination with a form over which to mold the toe of an upper off the last, of end embracing wipers and means for operating them to wipe the marginal portion of the toe of an upper inwardly over the bottom of said form to produce a molded flange on the upper, means for clamping the margin of the upper upon the wipers and for drawing the upper over the form prior to the inward movement of the wipers, and means automatically operative in time relation to the wipers to relax the clamping pressure on the margin of the upper prior to any substantial inward movement of the wipers over the bottom of the form.
83. In an upper shaping machine, the combination with a form, of end embracing wipers, a clamping device for clamping the marginal portion of an upper on said wipers, means for effecting relative movement between the form and said wipers and clamping device to draw the upper over the form, means for operating the wipers to wipe the upper inwardly over the bottom of the form, and controlling means for said clamping device automatically operative to relax the clamping pressure on the upper while maintaining said device in position to bend the upper over the edges of the wipers in the inward movement of the wipers.
84. In an upper shaping machine, the combination with a form, of end embracing wipers, a clamping device for clamping the marginal portion of an upper on said wipers, means for effecting relative movement between the form and said wipers and clamping device to draw the upper over the form, means for moving said wipers and the clamping device inwardly to wipe the upper over the bottom of the form, and means automatically operative to relax the pressure of said clamping device on the upper prior to any substantial inward movement of the wipers.

and to move said device away from the upper after the wipers have substantially completed their inward movement.

85. In a molding machine, the combination 5 with a form and end embracing wipers constructed and arranged to mold the margin of an end portion of an upper off the last to produce a flange upstanding from the bottom face of the form, of a device for clamping the 10 margin of the upper upon the outer face of the wipers, said clamping device being mounted for movement with the wipers inwardly over the form, and means for imparting to said clamping device a movement away from 15 the plane of the wipers in a direction oblique to said plane to cause the device to clear the upstanding flange.

86. In an upper shaping machine, the combination with end-embracing wipers for wiping 20 an end portion of an upper inwardly about a form, of a device for clamping the margin of the upper outspread upon the outer face of said wipers in the wiping operation, and means for moving said clamping device 25 toward and from the plane of the wipers while maintaining its upper-engaging face in substantially parallel relation to said plane with a substantial component of inward and outward movement along said plane toward and 30 from the wiping edges of the wipers in moving toward and from clamping position respectively.

87. In an upper shaping machine, the combination with end embracing wipers, of a pair 35 of clamp members for clamping the margin of an upper on the wipers, and supports for said clamp members comprising links arranged to impart inward and outward movements to said members in directions inclined 40 to the plane of the wipers as the members are moved toward and from the plane of the wipers while positioning said members continuously in substantially parallel relation to 45 said plane.

88. In an upper shaping machine, the combination with end embracing wipers for wiping 50 an upper over a form, wiper carriers on which said wipers are mounted, and means for operating said wiper carriers to impart inward and outward movements laterally of the 55 form to the wipers, of means for clamping the marginal portion of an upper on said wipers, said clamping means being mounted on the wiper carriers to move inwardly and outwardly with the wipers and to move toward and from the wipers in directions oblique to the plane of the wipers.

89. In an upper shaping machine, the combination with end embracing wipers for wiping 60 an upper over a form, wiper carriers on which said wipers are mounted, and means for operating said wiper carriers to impart inward and outward movements laterally of the form to the wipers, of members for clamping 65 the marginal portion of an upper upon

said wipers, supporting arms on which said clamp members are mounted, means on the wiper carriers for supporting said arms for swinging movements toward and from the plane of the wipers, and controlling means arranged for operative engagement with said arms in all positions of the wipers and the clamp members. 70

90. In an upper shaping machine, the combination with end embracing wipers, of 75 clamp members for clamping the marginal portion of an upper on the wipers and mechanism for moving said clamp members toward and from the wipers comprising connections adjustable to effect a relative variation of the clamping pressure on different portions of the upper. 80

91. In an upper shaping machine, the combination with end embracing wipers, of 85 clamp members for clamping the marginal portion of an upper on the wipers, an operating arm for each clamp member, and independently yieldable connections between said arm and different portions of the clamp member. 90

92. In a machine for shaping the toes of uppers, the combination with toe embracing wipers, of clamp members for clamping the marginal portion of an upper on the wipers, and operating means for said clamp members comprising yielding connections adjustable to effect a relative variation of the clamping pressure as between the sides and the end of the toe. 95

93. In a machine for shaping an upper 100 over a form, a device for embracing an end portion of an upper about the form and for wiping the upper heightwise of the form, said device being mounted for bodily movement laterally of the form in response to pressure of the upper against it. 105

94. In a machine of the class described, the combination with a form, of a band for embracing the toe of an upper about the form and for wiping the upper heightwise 110 of the form, and a support for said band mounted for movement laterally of the form in the wiping operation in response to differences in pressure of the upper against the opposite side portions of the band. 115

95. In a machine of the class described, the combination with a form, of a device for embracing the toe of an upper about the end of the form and for wiping the upper heightwise of the form, said device being adjustable 120 to a contour substantially complementary to the contour of the form lengthwise of its bottom edge, and means for holding said device rigidly against alteration of its contour during the wiping operation. 125

96. In a machine of the class described, the combination with a form, of a wiping band for embracing the toe of an upper about the form and for wiping it heightwise of the form, and means for holding said band 130

- rigidly against movement lengthwise of the form while permitting it to shift bodily in directions laterally of the form in the wiping operation.
97. In a machine of the class described, the combination with a form, of a device for embracing the toe of an upper and for wiping it heightwise of the form, said device comprising members mounted for swinging movements laterally of the form, spring means tending to swing said members outwardly, and stop mechanism adjustable to determine the positions of said members.
98. In a machine of the class described, the combination with a form, of a device for embracing the toe of an upper and for wiping it heightwise of the form, said device comprising members mounted for swinging movements laterally of the form, and means for holding said members positively against outward movement away from the form in the wiping operation.
99. In a machine for shaping an end of an upper over a form, an end embracing clamp comprising members mounted for swinging movements laterally of the form, and means for determining adjustably the positions of said members comprising plungers extending lengthwise of the form and adjusting screws carried by the members and arranged to bear against said plungers.
100. In a machine for shaping an end of an upper over a form, an end embracing clamp comprising clamp members mounted to swing laterally of the form and having means fast thereon for engaging an upper, a controlling member rigidly connected to the intermediate portion of said clamp and mounted for movement lengthwise of the form, and positive connections for determining the position of said controlling member and for additionally determining the positions of said clamp members with respect to swinging movement.
101. In an upper shaping machine, the combination with means for shaping an upper over a form comprising means for clamping different portions of the upper against the form, of controlling means automatically operative to relax the clamping pressure on a portion of the upper while the upper is held by clamping pressure applied on another portion to permit it to set in its acquired shape.
102. In an upper shaping machine, a device for clamping an upper about the end of a form, means for confining and holding the marginal portion of the upper, and automatic power-operated means for relaxing the pressure of said clamping device on the upper while the upper is held by the pressure applied on its marginal portion.
103. In an upper shaping machine, a power-operated device for clamping an upper about the end of a form, wipers for wiping the marginal portion of the upper inwardly over the form and for holding the upper while it sets, and automatic controlling means to cause said clamping device to relax its pressure on the upper after the wipers have wiped the marginal portion of the upper inwardly and while the wipers continue to hold the upper.
104. In an upper shaping machine, a device for embracing the toe end of an upper and for wiping the upper heightwise of a form and clamping it about the form, wipers for wiping the marginal portion of the upper inwardly over the form and for holding the upper while it sets, and means automatically operative in time relation to said wipers to relax the pressure of said clamping device on the upper while the wipers continue to hold the upper.
105. In an upper shaping machine, a device for clamping an upper about the end of a form, wipers for wiping the marginal portion of the upper inwardly over the form, power means for operating said wipers and for controlling said clamping device to cause it to relax its pressure on the upper in time relation to the inward movement of the wipers, and means for thereafter bringing the machine to a stop with said pressure relaxed and the wipers holding the upper to permit the upper to set in its acquired shape.
106. In a power operated toe molding machine, the combination with a form, of a wiping band for embracing the toe of an upper about the form and for wiping the upper heightwise of the form, wipers and means for operating them to wipe the marginal portion of the upper inwardly over the form while the upper is held by said band, and means for automatically relaxing the pressure of said band upon the upper and for then bringing the machine to a stop while the wipers continue to hold the upper.
107. In a machine of the class described, the combination with a form over which to shape the toe of an upper, and operating means for moving said form in the direction of its height, of a toe embracing device normally positioned to wipe the upper about the form as the form is thus moved, and controlling means automatically operative to move said toe embracing device away from the upper after the wiping operation and subsequently to return said device to its initial position ready for operation on another shoe.
108. In a power operated toe molding machine, the combination with a form, of a device for embracing the toe end of an upper and for wiping the upper heightwise of the form, wipers for wiping the marginal portion of the upper inwardly over the form, controlling means automatically operative to bring the machine to a stop to permit the upper to set, and means automatically opera-

tive before the machine comes to a stop to relax the pressure of said toe embracing device on the upper and when the machine is again started to restore said device to its initial condition ready to operate on another shoe.

109. In a toe molding machine, the combination of a form and end embracing wipers constructed and arranged to mold the marginal portion of an upper round the end of the toe in angular shape to conform substantially to the angle between the feather and the rib of an insole, and a support for said form constructed to permit assembled upper materials to be positioned about the form for the molding operation and to be thereafter removed from the form while the form remains on its support.

110. In a machine for molding the toe portion of assembled upper materials, the combination of a form having on its bottom portion a shoulder spaced inwardly from the outer edge of the form and extending round the end of the form from one side of the form to the other, wipers for wiping the toe end portion of upper materials inwardly over the form and against said shoulder to produce a marginal flange upstanding with respect to the bottom face of the form, and a support for the form constructed and arranged to leave an unobstructed space rearwardly of the top portion of the form to permit assembled upper materials to be mounted on and removed from the form.

111. In a toe molding machine, the combination of a form having on its bottom face a shoulder spaced inwardly from the outer edge of the form and extending round the end of the form from one side of the form to the other, and means for wiping the upper heightwise of the form and inwardly against said shoulder to mold the upper with a marginal flange upstanding with respect to the bottom face of the form.

112. In a toe molding machine, the combination of a form having on its face a shoulder spaced inwardly from the outer edge of the form and extending round the end of the form from one side of the form to the other, a device for wiping the upper heightwise of the form and for then holding the upper about the end of the form, and end embracing wipers for thereafter wiping the marginal portion of the upper inwardly over the form and against said shoulder to mold the upper with a marginal flange upstanding with respect to the bottom face of the form.

113. In a toe molding machine, the combination of inner forming means having substantially the contour of a shoe toe and constructed for molding the marginal portion of an upper in angular shape to conform substantially to the feather and the rib of an insole, means for clamping the marginal portion of the upper and for drawing the upper

over said inner forming means, and means for thereafter wiping the marginal portion of the upper inwardly and in co-operation with said inner forming means molding it in said angular shape.

70

114. In a toe molding machine, the combination of inner forming means having substantially the contour of a shoe toe and constructed for molding the marginal portion of an upper in angular shape to conform substantially to the feather and the rib of an insole, means for clamping the marginal portion of the upper and for drawing the upper over said inner forming means, a device for embracing the toe of the upper and wiping it heightwise over said inner forming means, and end embracing wipers for thereafter wiping the marginal portion of the upper inwardly and in co-operation with said inner forming means molding it in said angular shape.

75

80

85

115. In a toe molding machine, the combination of a form having along its bottom edge molding faces in angular relation to each other and extending round the form from one side to the other for molding the margin of an upper in angular shape to conform substantially to the feather and the rib of an insole, wipers co-operating with said faces to mold the upper, and means for effecting relative movement of said form and wipers in the direction of the height of the form to compress the upper.

90

95

116. In a toe molding machine, the combination of a form having along its bottom edge molding faces in angular relation to each other and extending round the form from one side to the other for molding the margin of an upper in angular shape to conform substantially to the feather and the rib of an insole, wipers co-operating with said faces to mold the upper, and operating means for moving said wipers inwardly to mold the upper against said faces and for moving said form in time relation to the wipers transversely of the plane of the wipers to increase the molding pressure on one of said faces.

100

105

110

117. In a machine of the class described, the combination with end embracing wipers, of wiper operating means comprising a toggle, one arm of which is arranged to impart operative movement to the wipers, and a spring arranged to receive the thrust of the other arm of the toggle.

115

118. In a machine of the class described, the combination with end embracing wipers, of a thrust member for imparting operative movement to said wipers, a yielding element, and a toggle between said yielding element and thrust member for operating the thrust member under control of said yielding element.

120

125

119. In a molding machine, the combination with end embracing wipers, of inner forming means constructed to present an

130

- abutment against the thrust of said wipers for molding the margin of an upper with an upstanding flange, and operating mechanism for said wipers including a member arranged 5 to yield in response to resistance encountered by the wipers.
120. In a molding machine, the combination with end embracing wipers, of inner forming means provided with a rigid abutment arranged to co-operate with the wipers to mold the margin of an upper with an upstanding flange, and operating mechanism for said wipers comprising a toggle and a spring associated with said toggle and 10 arranged to yield in response to resistance encountered by the wipers.
121. In an upper shaping machine, the combination with means for shaping an upper off the last, of means automatically 15 operative in time relation to said upper shaping means to trim the margin of the upper after the upper shaping operation.
122. In an upper shaping machine, the combination with end embracing wipers for 20 wiping the marginal portion of the toe of an upper inwardly over a form, of an upper trimming cutter, and means for operating said cutter in automatically determined time relation to the wipers to trim the margin of 25 the upper after it has been wiped inwardly.
123. In an upper shaping machine, the combination with means for shaping an end 30 of an upper to produce a marginal flange extending heightwise of the upper round its end, of means automatically operative in time relation to said upper shaping means to trim 35 said marginal flange by a cut extending along said flange from one side of the end of the upper to the other side.
124. In an upper shaping machine, the combination with wipers for gathering and 40 wiping an end portion of an upper inwardly over a form, of an upper trimming cutter mounted for movement in a fixed path along 45 the edges of said wipers to trim the margin of the upper substantially in the plane of the outer face of the wipers.
125. In an upper shaping machine, the combination with means for shaping an end 50 portion of an upper to produce a marginal flange extending heightwise of the upper round its end, of trimming means comprising 55 a cutter mounted for movement in a fixed path along the margin of the upper to trim said margin progressively from one side to the other of the end of the upper, and means for moving the cutter along said path.
126. In an upper shaping machine, the combination with means for gathering and 60 wiping the marginal portion of an upper inwardly over a form, of an upper trimming cutter mounted for movement in a fixed path to cut outwardly through the margin of the upper at one side of the end of the upper 65 and then to trim said margin progressively to the other side of the end of the upper.
127. In an upper shaping machine, the combination with wipers for wiping the margin of an end portion of an upper inwardly over a form to produce an upstanding flange 70 along the margin, of an upper trimming cutter comprising a cutting blade rotatably mounted to swing outwardly through the margin at one side of the end of the upper and then to cut progressively along said margin substantially in the plane of the outer face of the wipers to the other side of the end of the upper.
128. In an upper shaping machine, the combination with means for shaping an end 80 portion of an upper over a form, of an upper trimming cutter movable in a predetermined path along the margin of the upper from one side to the other of the end of the upper, and operating means for moving said cutter along 85 said margin and for then moving it reversely to its starting position.
129. In an upper shaping machine, the combination with means for shaping the toe 90 end of an upper over a form, of an upper trimming cutter having a movement automatically controlled to trim the margin of the upper by a cut terminating in front of the tip seam of the upper at each side of the toe.
130. In an upper shaping machine, the combination with means for shaping an end 95 of an upper over a form, of an upper trimming cutter, means automatically operative to move said cutter to trim the upper progressively between predetermined points at opposite sides of the end of the upper, and means for varying the extent of movement of said cutter.
131. In an upper shaping machine, the combination with wipers for gathering and 105 wiping the margin of an upper inwardly over a form, of a rotary upper trimming cutter automatically controlled to trim the margin 110 of the upper in predetermined relation to the plane of the wipers irrespective of the position of the form.
132. In an upper shaping machine, the combination with a form, of end embracing wipers for wiping the margin of an upper inwardly over the form, means for effecting 115 relative movement of said form and wipers in the direction of the height of the form, and an upper trimming cutter automatically controlled to trim the margin of the upper in predetermined relation to the plane of the wipers irrespective of the relative positions 120 of the form and the wipers.
133. In an upper shaping machine, the combination with wipers for gathering and 125 wiping the margin of an upper inwardly over a form, of an upper trimming cutter movable to operative position in a direction trans-

verse to the plane of the wipers, and stop mechanism for positioning said cutter in predetermined relation to the wipers irrespective of the position of the form.

134. In an upper shaping machine, the combination with a form, of end embracing wipers for wiping the margin of an upper inwardly over the form, means for moving the form transversely of the plane of the wipers, an upper trimming cutter movable with said form, and controlling means automatically operative to position the cutter in predetermined relation to the plane of the wipers irrespective of the position assumed by the form.

135. In a toe molding machine, the combination with a form over which to mold the toe of an upper, of a cutter permanently associated with said form for movement in a predetermined path to trim the margin of the upper, and means for molding an upper over the form and for positioning its margin in the path of the cutter.

136. In a toe molding machine, the combination with a form, of a support on which said form is mounted, means for molding an end of an upper over the form, and an upper trimming cutter also mounted on said form support for trimming the margin of the upper.

137. In a toe molding machine, the combination with a form, of a supporting stem on which said form is mounted, means for shaping the toe of an upper over the form, and a cutter mounted to turn about said stem to trim the margin of the upper.

138. In a toe molding machine, the combination with a form, of a support on which said form is mounted, means for shaping the toe of an upper over the form, a cutter mounted on said form support for trimming the margin of the upper, and power means for operating said cutter.

139. In an upper molding machine, the combination with molding instrumentalities for engaging and molding the marginal portion of an upper between them, of a cutter mounted in predetermined relation to said molding instrumentalities for trimming the margin of the upper while it is held under molding pressure between said instrumentalities.

140. In a toe molding machine, the combination with a form having on its bottom face an abutment against which to mold the margin of an upper to produce an upstanding flange, of wipers co-operating with the form to mold the margin against said abutment, and a cutter mounted for movement in a predetermined path to trim the margin of the upper while it is held between said abutment and the wipers.

141. In a toe molding machine, the combination with molding instrumentalities and power means for effecting relative movement

of said instrumentalities to mold the toe of an upper in substantially the shape which it is to have in the finished shoe, of trimming means automatically operative in time relation to said molding instrumentalities to trim the marginal portion of the upper.

142. In an upper shaping machine, the combination with means for shaping an end of an upper over a form, of an upper trimming cutter mounted for movement in a fixed path to trim the margin of the end of the upper and to leave the waste material attached to the upper.

143. In a toe molding machine, the combination with a form and means for molding the toe of an upper over the form to produce a marginal flange upstanding with respect to the bottom face of the form, of upper trimming means movable in a fixed path to trim the margin of the upper between predetermined points at opposite sides of the toe and to leave the waste material attached to the upper.

144. In a toe molding machine, the combination with a form and means for molding the toe of an upper over the form to produce a marginal flange upstanding with respect to the bottom face of the form, of a cutter automatically controlled for operation in a single plane to trim said margin and to leave the waste material attached to the upper.

145. In a machine for molding uppers, the combination with a form, and means for molding an upper over the form, of an ejector carried by the form and arranged to be projected from the contour face of the form to detach the upper from the form.

146. In a machine for molding uppers, the combination with a form, and means for molding the toe of an upper over the form, of a member arranged to be projected from the toe end face of the form to detach the upper from the form.

147. In a machine for molding the toes of uppers, the combination with a toe end form, and means for shaping the toe of an upper over the form, of an abutment arranged to bear against the rear end of the form to hold the form against the pressure of the upper shaping means.

148. In a machine for molding the toes of uppers, the combination with a toe end form, and wipers for wiping an upper inwardly about the front end of the form, of a support on which the form is mounted, and an abutment arranged to bear additionally against the rear end of the form to hold the form against the thrust of the wipers.

149. In a machine for shaping an upper over a form, the combination with means for applying shaping pressure to the upper, of means for trimming the upper comprising a cutter mounted for movement in a fixed path lengthwise of the edge of that portion of the upper upon which it operates to trim the up-

per by a cut substantially parallel to said edge.

150. In a machine for shaping an upper over a form, the combination with means for applying shaping pressure to the upper, of means for trimming the upper comprising a cutter mounted for movement in such a path

as to trim the upper by a cut extending lengthwise of the edge of the upper and so disposed as to leave the waste material attached to the upper. 10

In testimony whereof I have signed my name to this specification.

WILLIAM C. BAXTER.

CERTIFICATE OF CORRECTION.

Patent No. 1,692,284.

Granted November 20, 1928, to

WILLIAM C. BAXTER.

It is hereby certified that error appears in the printed specification of the above numbered patent requiring correction as follows: Page 12, line 35, claim 7, strike out the word "means"; page 20, line 46, claim 112, before the word "face" insert the word "bottom"; and that the said Letters Patent should be read with these corrections therein that the same may conform to the record of the case in the Patent Office.

Signed and sealed this 20th day of August, A. D. 1929.

(Seal)

M. J. Moore,
Acting Commissioner of Patents.

per by a cut substantially parallel to said edge.

150. In a machine for shaping an upper over a form, the combination with means for applying shaping pressure to the upper, of means for trimming the upper comprising a cutter mounted for movement in such a path

as to trim the upper by a cut extending lengthwise of the edge of the upper and so disposed as to leave the waste material attached to the upper.

In testimony whereof I have signed my name to this specification.

WILLIAM C. BAXTER.
